UNITED STATES PATENT OFFICE.

ARTHUR H. ADAMS, OF NEW YORK, N. Y., ASSIGNOR TO WESTERN ELECTRIC COMPANY, OF CHICAGO, ILLINOIS, A CORPORATION OF ILLINOIS.

HEAT-COIL.

No. 851,051.

Specification of Letters Patent.

Patented April 23, 1907.

Application filed October 9, 1905. Serial No. 281,932.

To all whom it may concern:

Be it known that I, ARTHUR H. ADAMS, a citizen of the United States, residing at New York, in the county of New York and State 5 of New York, have invented a certain new and useful Improvement in Heat-Coils, of which the following is a full, clear, concise, and exact description.

My invention relates to heat-coil protective devices for electrical circuits, and has for its object the provision of a reversible heat-coil and means whereby it may be conveniently held in position on the protective apparatus.

15 My invention contemplates, generally speaking, means by which a reversible heat-cartridge may be conveniently held in place on the ordinary protector-strip, thus rendering it possible to use with standard apparatus, designed more particularly for non-reversible heat-coils, those of either reversible or non-reversible type.

25 Considered more specifically, my invention consists in providing a cap for the heat-coil, slidable over either end thereof and forming an extension of the same. This cap forms a support for one end of the heat-coil and is itself adapted to be supported by a spring of the protective apparatus. The heat-coil co-

30 operating with the cap of my invention consists of a hollow spool with a heat-producing winding upon the same and a pin inserted in the spool and secured thereto by a fusible material, so as to project unequal distances 35 from the end of the spool. The cap is slipped over that end of the heat-coil from which the pin projects farther. When the heat-coil is in position on the protective apparatus, the cap is under pressure of a spring tending to

40 push it farther over the spool; but under normal conditions this is prevented by the projecting pin. When an abnormal current passes through the heat-coil, the fusible material melts, and the cap is pressed forward 45 over the spool by the spring pushing the pin through the spool and grounding the current. When the fusible material cools, it resolders the pin in the core, restoring the heat-coil to a serviceable condition, so that upon merely 50 reversing it in the cap it is again ready for use.

I will describe my invention more particu-

larly by reference to the accompanying drawings, in which—

Figure 1 is a side elevation of a series of 55 protective apparatus provided with my invention, parts being broken away to more clearly show the same. Fig. 2 is a front view showing a heat-cartridge equipped with my invention in connection with a protector-strip, there being a pair of protectors mounted on each side of the strip. Fig. 3 is a detail longitudinal section of a heat-cartridge in position in the mounting means of my invention. Fig. 4 is a cross-section on line 4 4 60 65 of Fig. 3.

The core or spool *a* has a coil of heat-producing wire *b* wound around it, one end of said wire being secured to the core and the other to a cylinder *c*, inclosing the coil and 70 insulated from the core by the hard-rubber disks *d*, serving as ends for the drum or cylinder *c*. The ends of the core project equal distances from the ends of the drum. The spool *a* has a central bore within which is inserted a pin *e*, secured within the spool by readily-fusible solder *f*, so that the ends of 75 the pin project unequal distances beyond the ends of the core.

Coöperating with the heat-coil is a metallic 80 cap consisting of a disk *g*, having spring-arms *h* extending at right angles thereto and frictionally engaging the cylinder, so as to slide thereon. A block *i* of insulating material is secured within the cap in proximity to the 85 disk *g*. This block has an opening therein to receive the longer end of the pin *e*. A portion of the block *i* projects through an opening in the disk *g* and constitutes a support *j*.

In using the coil the cap is slipped over 90 that end of the heat-coil from which the pin *e* projects farther until the end of the pin rests in the opening of the block *i*. The combined cap and coil is then placed in position between the springs *k l* of a protective apparatus of the well-known form shown in the drawings, the support *j* resting in the slot *m* of the spring *l*. The spring *l* presses inward against the disk *g*, and one end of the spool *a* bears against the spring *k*. The pin *e* passes 95 through an opening in the spring *k* and bears against the spring *n*.

When the heat-coil is in position on the protective apparatus, as above described, a

circuit is completed between the spring *l* and springs *k* and *n* through disk *g*, cylinder *c*, winding *b*, spool *a*, and pin *e*. If a current of sufficient strength to be injurious to the apparatus with which the protective device is used pass through the heat-coil, the copper core *a* will become heated sufficiently to fuse the solder *f*. The pin is then free to move in the spool, and the pressure of spring *l* against disk *g* will force the cap farther over the cylinder *a*, as shown in dotted lines in Fig. 3, until the pin *e* forces the spring *n* in contact with the plate *o* and grounds the line in the usual manner.

15 When the solder becomes cool, it resets and reunites the pin *e* to the core *c*, with the ends of the pin projecting at unequal distances in a reversed position therefrom. By the operation of the coil, therefore, the position of the pin in the core is merely reversed, and by removing the cap and slipping it over the other end of the coil the device may be used as before.

Since the heat-coil and its coöperating cap are distinct, should either part become defective it may be readily renewed without necessitating the renewal of the other.

What I claim is—

1. In a protector for electrical circuits, a 30 heat-coil having a slidable pin adapted to project from either end thereof, of a cap slidably engaging said heat-coil to bear against said pin, said heat-coil being reversible in said cap.

35 2. In a protector for electrical circuits, a heat-coil cartridge comprising a spool, a heating-conductor for said spool, a slidable member passing through the spool and adapted to project at either end thereof, means for 40 normally fastening said member to the spool, and a cap slidably engaging said spool and bearing against said slidable member to actuate the same under abnormal conditions.

3. In a protector for electrical circuits, the 45 combination with a heat-coil having a pin projecting from the end thereof, of a cap comprising a disk having spring-arms adapted to slidably engage said heat-coil, and a disk of insulating material secured within the cap 50 and having an opening for receiving the projecting end of the pin.

4. In a protector for electrical circuits, a heat-coil cartridge comprising a spool, a heating-conductor for said spool, a pin passing through the spool and adapted to project 55 at either end thereof, fusible material fasten-

ing said pin to the spool, and a cap adapted to slide over either end of the spool and bear against the projecting end of the pin to actuate the same under abnormal conditions, 60 whereby one operation places said cartridge in condition to be reversed in said cap.

5. In a heat-coil, the combination with a hollow spool, of a heat-producing coil wound thereon, one end of which is secured to said spool, a drum inclosing the heat-producing coil and to which the other end of the heat-producing coil is secured, a pin extending through the spool with its ends projecting unequal distances, fusible material securing 70 the pin to the spool, a cap slidably mounted on the drum and receiving in an insulated bearing the longer projecting end of the pin, and means for sliding the cap over the heat-coil, under abnormal conditions, to reverse the 75 distances which the pin projects from the ends of the spool, and thereby controlling a circuit.

6. In a protector for electrical currents, the combination with a protector-strip, of a 80 heat-cartridge and a support for one end of said cartridge, said support being constructed to engage said strip and being reversible with relation to said cartridge.

7. The combination with a protector-strip 85 and a reversible heat-cartridge therefor, of separate means forming a support for one end of said cartridge, said means having a portion constructed to engage with said protector-strip, and said heat-cartridge being 90 reversible with relation to said supporting means.

8. The combination with a protector-strip, of an attachment for heat-cartridges comprising a portion constructed to engage a 95 heat-cartridge and a portion for engagement with said protector-strip, the ends of said heat-cartridge being reversible with relation to said attachment after each operation of the cartridge.

9. In a protector for electrical currents, the combination with a heat-cartridge, of a reversible mounting-cap having spring-arms adapted to slidably engage said heat-cartridge.

In witness whereof I hereunto subscribe my name this 25th day of July, A. D. 1905.

ARTHUR H. ADAMS.
